Atty.

UNITED STATES PATENT OFFICE.

OLIVER ANDERSON, OF FORT TOTEN, DAKOTA TERRITORY, ASSIGNOR OF
ONE-HALF TO FRED. C. STANDISH, OF SAME PLACE.

BAG-FASTENER.

SPECIFICATION forming part of Letters Patent No. 375,976, dated January 3, 1888.

Application filed October 26, 1887. Serial No. 253,457. (No model.)

To all whom it may concern:

Be it known that I, OLIVER ANDERSON, a citizen of the United States, residing at Fort Totten, in the county of Ramsey and Territory 5 of Dakota, have invented new and useful Improvements in Bag-Fasteners, of which the following is a specification.

This invention has for its object to provide a novel bag fastener from a single piece of wire; and the invention consists in a bag-fastener made from a single piece of wire bent into spring-coils, from which extend two spring-arms, one formed with an eye or loop through which the other arm extends to prevent its lateral or sidewise twisting, and one arm having at its extremity a hook to engage with the extremity of the other arm, as will more fully hereinafter appear.

In the accompanying drawings, Figure 1 is 20 a perspective view showing the fastener applied to a bag to close the mouth thereof; and Fig. 2, a perspective view of the fastener, showing the spring-arms disengaged and ready to be applied to a bag.

In order to enable those skilled in the art 25 to make and use my invention, I will now describe the same in detail, reference being made to the accompanying drawings.

I take a single piece of spring steel, copper, 30 or other wire of suitable length for the conditions required, and between its ends bend it into a series of spring-coils, 1, and two spring-arms, 2 and 3, the arm 3 adjacent to the coils being bent into an obliquely-arranged loop or 35 eye, 4, through which extends the other arm, 2. The loop or eye allows the arms to move to and from each other and prevents the arms from undue twisting movement laterally or sidewise. The spring-coils constitute a handle 40 for the device; but, in addition thereto, the

coils impart the desired resiliency to the arms that their tendency is to stand apart as in Fig. 2, so that they are constantly in proper position to be applied over the bag-mouth and pressed together and fastened, which latter is 45 accomplished by providing the extremity of the arm 2 with a lateral bend, 4^a, formed into a hook, 5, which can be lifted over and engaged with the extremity of the other arm, 3. This affords space between the arms for the 50 folds of the bag-mouth when drawn up to apply the fastener. The engagement of the arms with each other is such that the bag-mouth will be securely held and the arms cannot become accidentally disengaged by rough handling of the bag.

By my invention I construct the fastener of one piece of wire, and thus avoid pivot-pins or hinges for connecting two arms of a bag-fastener, as has heretofore been proposed, and, 60 further, the coiled connection of the arms is such that the latter immediately spring apart when disengaged, so that they are always in proper position to be applied to the bag.

Having thus described my invention, what 65 I claim is—

A bag-fastener consisting of two arms connected by coils to spring the arms apart, one arm having a loop or eye adjacent to the coils, through which the other arm passes, and one 70 arm having a hooked extremity to pass over and engage the extremity of the other arm, substantially as described.

In testimony whereof I affix my signature in presence of two witnesses.

OLIVER ANDERSON.
